Simon T. Sutton

UNITED STATES PATENT OFFICE.

SIMON T. SUTTON, OF CHICAGO, ILLINOIS.

FULL TIGHTS.

SPECIFICATION forming part of Letters Patent No. 402,202, dated April 30, 1889.

Application filed November 8, 1887. Serial No. 254,617. (No model.)

To all whom it may concern:

Be it known that I, SIMON T. SUTTON, a citizen of the United States, residing at Chicago, in the county of Cook and State of Illinois, have invented certain new and useful Improvements in Full Tights; and I do declare the following to be a full, clear, and exact description of the invention, such as will enable others skilled in the art to make and use the same, reference being made to the accompanying drawings, and to the letters and figures marked thereon, which form a part of the specification.

The object of my invention is to provide an improved article of manufacture styled in theatrical circles and known to the trade as "full tights," and my invention consists in the improved article constructed as herein-after specified and claimed.

In carrying out my invention I knit the article, preferably making use of a knitting-machine—as, for instance, the Lamb knitting-machine—to knit the entire article, or in certain cases the complete article with the exception of the draw-cord that may be sometimes employed and serve to tighten or fasten it about the waist of the wearer. Exact measurements in certain instances are made of the individual for whom the full tights are intended to fit, including the waist and proceeding downward to the pedal extremities, taken every few inches apart or at such distances as will give a close approximation in estimating the proportions of the article or garment to fit the waist, hips, thighs, knees, legs, and feet, including the toe portions. This is to serve as a guide in the knitting and formation of the garment in making the same to order, as is frequently the case in meeting the demands of the theatrical profession, of the athletic sporting fraternity, and others. When the full tights are made for the trade, they are shaped to certain regulation sizes, such as commercial custom recognizes in this line of goods. Taking one of these as an example, the process may be stated as illustrative of that practiced in making the various other regulation sizes, and as indicative, also, of that carried out in knitting and finishing the garment to exact measurements for an individual.

When a machine of the order known as the

"Lamb Knitting-Machine" is employed (a machine being preferred in manufacturing on a large scale) and a garment of a certain size is to be made, I set up three hundred and fourteen needles with which to commence the work, these needles being supplied with yarn in the usual manner and operated to produce a selvage edge at the top of the garment. I then knit about ninety rounds of circular work with the tight gage or with the cams set to produce short stitches, so as to make a close web. I then widen out twenty-two needles on each of the four corners of the machine, with six rounds between the addition of one needle and that of the next. Then I knit about ninety rounds, (depending upon the length of the waist,) this bringing the work down to the crotch. Then I run one-half of the work off. The stitches that are dropped—that is, of that part to be transferred back onto the machine—are held from raveling by a thread drawn through them, and then knitting is proceeded with to make one of the legs of the garment, which may be either the right or left leg, the narrowing being done on a line extending downward from the crotch, corresponding in position to that of the inside thigh and leg seam of ordinary tights and similar garments, and the foot and toe portions being knit in any of the ordinary ways. Then the stitches that were dropped and held from raveling by a thread drawn through them are transferred back onto the machine, and the other leg and foot of the garment are made in a similar manner.

The manner of knitting, narrowing, and finishing each of the legs of the garment—that is, those parts extending from the crotch to the pedal extremities—is preferably, in all essential respects, the same as that described and claimed in my application, Serial No. 252,627, filed October 17, 1887, and hence need not be particularly described here.

In the drawings, Figure 1 is a quarter front view of the garment as it appears when worn. Fig. 2 is a rear view of the garment, a part at the top being broken away to show the draw-cord as held in the upper hem.

A is the right leg of the garment, extending from the line *c c* at the crotch *d* down to the pedal extremity.

B is the left leg, corresponding in shape

and dimensions with the right leg. The line *a a* denotes the point at which the first ninety rounds of circular work ends in knitting the garment, the top edge of the knit work being produced with a selvage edge in using a Lamb knitting-machine by first binding off the three hundred and fourteen needles with which the work is commenced. The operation of "binding off" is the usual one of setting up the needles to form a selvage edge, and consists in first pushing up a needle as far as it will go, placing the yarn in its latch, and then pushing the needle down into its place in the bed of the machine, this operation being repeated after each of the needles set up. The extreme top portion is turned down on the inside and stitched to form a hem, *h*, about an inch in depth to form a draw-cord channel for the draw-cord whose ends *i* are designed to hang down inside of the garment, as shown in Fig. 2. This hem is usually made after the garment is otherwise completed.

From the line *a a* widening commences and extends to the line *b b*, the widening being produced on the above machine by twenty-two needles on each of the four "corners" of the machine with six rounds between the addition of each needle and that of the next. From the line *b b* plain circular work commences and extends to the line *c c*, about ninety rounds being knit, (depending upon the length of the waist,) this bringing the work down to the crotch *d*. *C* is that part of the garment extending from the top thereof approximately to the line *a a*, and is called the "waist" portion. *D* is that part extending approximately from the line *a a* to the line *c c*, and is called the "hip" portion. One half of the work at this point is run off the machine, whereupon the knitting of one of the legs is begun, and the leg as knitted is narrowed on the inside of the thigh portion on the line *d c* to the point *e*. Circular work then commences, extending to the point *f*. Then narrowing on the inside of the leg portion proper commences and extends down to the point *g* at the top of the ankle, after which the foot is knit and finished in any ordinary manner, or it may be made as fully described in the application above referred to. The stitches that were run off are now placed upon the needles again, and the other leg is then knit in a similar manner. The result of this method of manufacture is a pair of seamless tights, with the exception of the picked-up stitch-seams of the heels, that may be produced as stated in said application, and the line of stitching about the top of the upper portion in forming the hem *h*. Even these lines of stitching may be dispensed with, the top of the garment being thickened to such an extent in knitting it with tight gages as to obviate the necessity of a draw-cord or any other means of tightening it up to hold about the waist, and the foot portions being knit

without any seam or seams in any known manner.

The garment made in this manner—that is, either with or without the slight amount of stitching used in forming seams, as above stated—is one possessing qualities admirably adapting it to withstand the severe strains it is frequently subjected to by the wearer, as in the case of acrobats, contortionists, and 75 gymnasts, and persons generally engaging in athletic exercise or sports. The qualities are those due to the characteristic continuous knitting extending from the top of the garment to the feet, and including the latter, (with 80 possibly the exception in some cases of the picked-up stitching in the heels, and in some cases the hem about the waist,) with no seam anywhere in the garment in a position to be subjected to the strains most likely to prove 85 damaging to "tights," as those produced by the violent physical exertion or bending of the legs and body of the wearer—that is, the garment is without a seam either in front or rear of its waist and hip portion, while the 90 widening of that part, considered as a whole, is at the sides, thus adding much to its comeliness as a garment designed to fit closely to the skin, and as appearing, as far as may be, to form a part thereof, as well as adding to its 95 strength and reliability. The lines of greatest strain, extending upward from the crotch both in front and rear, are thus provided with continuous-knit material, making the garment of homogeneous texture and uniformly 100 elastic, and thus obviating the inelastic seaming, or the elastic but less secure seaming or stitching (as by picked-up stitches) heretofore used. These features, in connection with that of narrowing the legs *A B* on the lines of the inside thigh and leg portions of the garment, as at *d e* and *f g*, make the garment one of special value in theatrical and 105 sporting circles, because of its reliability in enduring strains without severing or "ripping of seams," and because of its symmetry 110 of outline enhancing its beauty.

It is to be understood that the garment may or may not be produced with a hem at its top for a waist draw-cord, and, also, that the 115 foot portions may be knit in any of the commonly-practiced methods, or said feet may be knit and have certain lines of picked-up stitching, as set forth and claimed in my pending application above referred to; hence 120 I do not desire my invention to be limited to the precise constructions of said parts or to any particular form thereof.

Having thus fully described my invention, what I claim, and desire to secure by Letters 125 Patent, is—

1. As an improved manufacture, knitted tights having a seamless waist portion of plain circular work and a seamless hip portion, the latter being widened out from the line *a a* to the line *b b*, or approximately so, substantially as shown and described.

2. As an improved manufacture, knitted tights having a seamless waist portion of plain circular work, and a seamless hip portion which is widened on the two opposite sides of the garment, substantially as shown and described.

3. As an improved manufacture, seamless knitted tights having a waist portion, C, of plain circular work commencing at the top of the garment and extending to the line *a a*, the hip portion D, widened from the line *a a* to the line *b b*, or approximately so, and then knit in plain circular work to the point or line *c c* at the crotch, substantially as shown and described.

4. As an improved manufacture, seamless knitted tights having a waist portion of plain circular work, a hip portion widened from the line *a a* to the line *b b*, or approximately so, and then plain circular work to the

line *c c* at the crotch, and the seamless legs narrowed on their insides from the crotch to the ankle portions, excepting at the knee portions between the lines *e e* and *f f*, which are of plain circular work, substantially as shown and described.

5. As an improved manufacture, seamless knitted tights having legs narrowed on their inside lines from the points *d* to the points *e*, and from points *f* to points *g*, and having waist and hip portions formed continuously therewith and of circular knitted work, substantially as shown and described.

In testimony whereof I affix my signature in the presence of two witnesses.

SIMON T. SUTTON.
